UNITED STATES PATENT OFFICE.

RICHARD F. TOBIN, OF SOUTH BOSTON, ASSIGNOR TO CALEB C. WALWORTH,
OF BOSTON, MASSACHUSETTS.

HOSE-NOZZLE ATTACHMENT.

SPECIFICATION forming part of Letters Patent No. 291,107, dated January 1, 1884.

Application filed February 16, 1883. (No model.)

To all whom it may concern:

Be it known that I, RICHARD F. TOBIN, of South Boston, county of Suffolk, State of Massachusetts, have invented an Improvement in Hose-Nozzle Attachments, of which 5 the following description, in connection with the accompanying drawings, is a specification, like letters on the drawings representing like parts.

10 My invention consists in the improved deflecting-plate hereinafter more particularly set forth and claimed.

In the drawings referred to, Figure 1 is a longitudinal section of a portion of a hose-nozzle and attachment embodying this invention, and Fig. 2 a plan view of the face of the distributing-disk, its supporting-arms being shown in section.

The hose-nozzle, *a*, of any usual construction, 20 is shown as threaded around its orifice to receive the threaded collar *b*, to which are attached the supporting-arms *c* of the deflecting plate or disk *d*, which is thus held in the path of the stream of water issuing from the nozzle, at a short distance in front of the orifice 25 of the said nozzle. The said deflecting-plate *d* is provided with a number of holes, *e*, through which a portion of the stream that issues from the nozzle passes forward, as shown by the 30 dotted lines 2, Fig. 1. The plate *d* has near its periphery water-guiding faces *h i k*, curved at different angles relative to the axis of the stream issuing from the nozzle, the portions *k* being continuations of the curvature of the main 35 surface of the plate. The water striking on the surface of the said plate passes off tangentially from the different guiding-surfaces *h i k* at different angles, as indicated by the dotted lines 3, Fig. 1, a portion coming back toward the hose-nozzle, and a portion passing off at about right 40 angles thereto, so that the water is spread over a large area, thereby wetting the under side of the roof or floor adjacent to the point where the hose-nozzle is inserted, and thus extinguishing the fire and rendering it safe for the firemen to enter the building. The face of the 45 plate *d* is also provided with deflecting projections *m*, by which a small portion of the water is thrown back, as shown by the dotted 50 lines 4, Fig. 1, directly toward the nozzle and

hose, thus keeping its outer surface wet and cool and preventing it from being burned.

It will be seen that by raising or lowering the nozzle through the opening the water issuing from the different surfaces *h*, *i*, and *k* 55 will strike the surface of the roof or floor at different distances from the orifice of the hose, so that the said surfaces will be thoroughly wet near to and at a considerable distance from the hose. The water issuing from the 60 surfaces *h* strikes the roof comparatively near the point where the hose is inserted, while that issuing from the surfaces *k* will pass nearly parallel with the wall to as great a distance as the velocity of the water will carry it, 65 and that issuing from the surface *i* strikes at intermediate points.

I claim—

1. The water-deflecting plate having cut 70 therein on its under side the guiding-grooves *h i k*, of different depths and curvatures, extending to the periphery of the said plate, combined with the arm *c*, to support the said plate across the path of the stream issuing from a hose or pipe, whereby the said stream 75 is thrown at different angles with relation to the direction of the issuance of the stream, as set forth.

2. A water-deflecting plate having cut 80 therein the grooves *h i k*, of different depths and curvatures, combined with the projections *m* and arms *c*, to support the said deflecting-plate across the path of a stream from a hose or pipe, substantially as shown, and for the purpose described.

3. A water-deflecting plate having cut 85 therein the grooves *h i k*, of different depths and curvatures, and the holes *e*, combined with the projection *m* and arms *c*, to support the said deflecting-plate across the path of the stream issuing from the hose or pipe, substantially as and for the purpose described.

In testimony whereof I have signed my name to this specification in the presence of two subscribing witnesses.

RICHARD F. TOBIN.
